O'Horo, Esq.*

UNITED STATES PATENT OFFICE

MATHEW J. WALSH, OF MILWAUKEE, WISCONSIN

DRESSING TOOL

Application filed April 25, 1931. Serial No. 532,780.

This invention pertains to tools for dressing or refacing the surfaces of grinding or abraiding wheels, which through use have become uneven or glazed, and also to the 5 method of manufacturing said tools.

The invention has primarily for its object to improve structures of the foregoing character, and more particularly such structures as disclosed in pending application Serial 10 No. 521,937, filed March 12, 1930, by the provision of a novel structure and design to materially increase the efficiency of such tools, and a simple, inexpensive method of manufacture for producing such structures at minimum cost.

Incidental to the foregoing, a more specific object resides in the provision of a dressing tool in which the working portion of the tool comprises a flat coiled strip having spaced outer peripheral prongs or teeth for engagement with the surface of an abraiding wheel.

A further object resides in the provision of a novel method of forming the dressing element, comprising subjecting a flat strip of metal to a pair of opposed dies to slit the material transversely and partially of its width, and thereafter coiling the strip edge-wise over an annular mandrel to cause the slit outer periphery to spread, and provide spaced teeth.

A more specific object resides in accomplishing the foregoing slitting operation by running a flat strip of metal through a pair of opposed annular dies.

With the above and other objects in view, which will appear as the description proceeds, the invention resides in the novel construction, combination and arrangement of parts substantially as hereinafter described and more particularly defined by the appended claim, it being understood that such changes in the precise embodiment of the 45 herein disclosed invention may be made as come within the scope of the claim.

In the accompanying drawing is illustrated one complete example of the physical embodiment of the present invention constructed according to the best mode so far devised

for the practical application of the principles thereof.

In the drawing, Figure 1 is a side elevation of one form of apparatus employed in practicing the present method of manufacture;

Figure 2 is a plan elevation of the strip of material after the same has been partially slit transversely of its width;

Figure 3 is a side elevation of the strip after the same has been coiled over a mandrel; and

Figure 4 is a front elevation of the finished dressing element.

Referring now more particularly to the accompanying drawing, the numeral 1 designates a flat strip of material from which the dressing element is to be formed. As shown in Figure 1, the strip 1 is subjected to a pair of opposed dies 2 which serve to form the slits 3 transversely of the width of the strip, and terminating intermediate its longitudinal edges approximately centrally thereof. The apparatus illustrated for forming the slits 3 comprises a pair of rotary dies which cooperate to form the slits. However, it is to be understood that the invention contemplates the use of any type or form of dies capable of accomplishing the same result, although rotary dies are preferable, due to the fact that they are capable of greater capacity.

After the material has been slit, as illustrated in Figures 1 and 2, the same is coiled over an annular mandrel (not shown) of substantially the same diameter as the hub 4. Obviously, any lead or pitch may be given to the coils, depending upon the thickness of the material used, and the diameter of the coils. The smaller the lead, the greater clearance between the coils and also the greater number of prongs or teeth, as will be hereinafter described.

In coiling the slotted strip over a mandrel, it will be quite apparent that the outer periphery of the coils, which is provided with the slits 3, will be caused to spread, resulting in the provision of the spaced prongs or teeth 5, which in the operation of the tool are held into immediate engagement with the surface of the abraiding wheel being dressed, as de-

scribed more in detail in the aforesaid pending application, and as indicated in Figure 3, it being understood that as the abraiding disc 6 is rotated, the dressing element held in engagement therewith will also be rotated, during which operation there is a lateral shifting of the surface of engagement between the abraiding disc and the prongs 5, during which action the prongs serve to cut or dress the peripheral surface of the disc 6.

It is believed that the advantages of the present structure over that disclosed in the aforesaid pending application will be quite apparent, in that the spaced teeth provide spaced cutting edges for engagement with the surface of the abraiding disc, thus presenting a more effective cutting tool than where a continuous cutting surface is employed, as illustrated and described in the aforesaid application.

It will also be readily seen that spaced teeth provide for ready clearance of the particles of abraiding material cut from the surface of the disc 6, thus allowing the tool to effectively clear itself and materially increase the cutting action.

After the strip 1 has been coiled, as disclosed in Figures 3 and 4, the same is mounted upon, and suitably secured to the hub 4, which hub is provided with end recesses 7 for reception of a suitable forked handle (not shown) to permit free rotation of the dressing element.

Thus, it will be seen that an extremely simple, inexpensive, and highly efficient dressing element has been provided, and which because of the novel method of manufacture can be produced at a minimum cost and with great speed, only two operations being required to form the same, namely, slitting the strip by means of dies, and thereafter coiling the same over a mandrel by any suitable mechanism.

I claim:

A tool for refacing abraiding wheels comprising a hub, a flat strip wound spirally upon the periphery of said hub, and radially projecting teeth on the outer edge of the strip, said teeth having its edges bevelled in opposite directions and provided with flat outer faces of substantially diamond shape.

In testimony that I claim the foregoing I have hereunto set my hand at Milwaukee, in the county of Milwaukee and State of Wisconsin.

55 MATHEW J. WALSH.
